UNITED STATES PATENT OFFICE.

WILLIAM ROWLAND EDWARDS, OF WEYBRIDGE, ENGLAND.

TERMINAL AND BINDING-SCREW FOR ELECTRIC BATTERIES AND CONNECTIONS.

SPECIFICATION forming part of Letters Patent No. 673,710, dated May 7, 1901.

Application filed November 2, 1900. Serial No. 35,282. (No model.)

To all whom it may concern:

Be it known that I, WILLIAM ROWLAND EDWARDS, a subject of the Queen of Great Britain, residing at Weybridge, in the county 5 of Surrey, England, have invented a certain new and useful Improvement in Terminals and Binding-Screws for Electric Batteries and Connections; and I hereby declare the following to be a full, true, clear, and exact description of the invention, such as will enable others skilled in the art to which it appertains to make and use the same.

My invention relates to the terminals and binding-screws used for making the connections in electric, galvanic, and storage batteries; and the object of my invention is to prevent the corrosion by acid fumes and acids used in the batteries of the exposed parts of the terminals and binding-screws, by 15 which they are rapidly destroyed and the goodness of the electrical connection is affected. I attain this object by the means illustrated in the accompanying drawings, in which—

25 Figure 1 is a side view of a binding-screw by which the leaden conducting-strips forming the connection between the parts of a galvanic or storage battery are held together. Fig. 2 is a longitudinal section of the same, 30 and Fig. 3 is a transverse section through the line A B in Fig. 2.

Similar letters refer to similar parts throughout the several views.

The central screw *a*, of brass, copper, iron, 35 or steel, is provided from end to end with a fine thread, one of its ends being screwed into the hollow nut *b*, the threaded opening in which does not pass completely through the nut, but is closed at the end at *c*. The screw 40 *a* is shown flattened at two of its opposite sides *d* and *e*, Fig. 3, to receive a key or spanner, by which it can be tightly screwed into the nut *c* or unscrewed. A second similar nut *f* can be screwed upon the other end of 45 the screw *a*. The inner faces of the nuts *c* and *f* are not flat, but are conically recessed at their centers, so as to leave a sharp projecting angular ridge *g* projecting above their surface.

50 *h i* are washers, of soft lead, passing freely over the screw *a* and resting against the faces of the nuts *b* and *f*.

k represents the lead strips or terminals which are to be connected together.

The nuts *b f* are flattened at two of their 55 opposite sides to afford facilities for holding them while being screwed up, or they may be made hexagonal or square. The nuts *b* and *f* are made of a non-corrosive metal or material, such as what is well known as "anti- 60 moniated lead," an alloy of lead and antimony, which while sufficiently hard to receive the screw-thread is not injuriously affected by the acid and acid fumes used in or escaping from the batteries. The screw *a* 65 having been tightly screwed into the nut *b* and the lead washer *h* passed over it and against the face of the nut, the lead connecting-strips *k* are fitted over the screw, the lead washer *i* is fitted against the outer strip, and 70 the nut *f* is screwed upon the end of the screw *a* and is tightened up until the sharp ridges *g* are pressed into the lead washers, forming a perfectly close and air-tight joint.

The connections can be quickly and easily 75 connected and disconnected, and no oxidation or deposit of acid salts takes place upon them, as has heretofore been invariably the case with the connections of galvanic and storage batteries, so that the terminals and 80 binding-screws always remain perfectly clean and are very durable.

My improvement is applicable to terminals or binding-screws for all kinds of electrical connections in electric batteries or accumulators.

What I claim, and desire to secure by Letters Patent, is—

1. In a terminal or binding-screw for electric batteries, the combination with a screw-threaded pin, of a nut secured to one end of said pin, a second nut interiorly screw-threaded adapted to engage with the threads on the other end of the pin, and washers of soft conducting material interposed between the inner faces of said nuts, the said second nut being provided with an annular ridge on its inner face, substantially as described.

2. In a terminal or binding-screw for electric batteries, the combination of a pin screw-threaded at both ends, a pair of interiorly screw-threaded closed nuts or caps having conically-recessed inner faces, and a pair of pliable washers of conducting material inter-

posed between said closed nuts or caps, substantially as described.

3. In a terminal or binding-screw for electric batteries, the combination of a screw-threaded pin having flattened ends, a pair of interiorly-screw-threaded closed nuts or caps, the said nuts or caps being provided on their inner faces with an annular ridge or projection, and a pair of pliable washers of conducting material interposed between said closed nuts or caps adapted to engage and conform with the surface of the inner faces of the nuts or caps for making a non-corrosive connection, substantially as described.

4. The combination in a terminal or binding-screw for electric batteries and connections, of the fine-threaded screw *a*, the nuts *b* and *f* having threaded recesses to receive the ends of the screw *a*, the projecting angular ridges *g* upon the inner faces of the nuts *b* and *f*, and the soft-lead washers *h* and *i*, substantially as set forth and shown.

In witness whereof I have hereunto set my hand in the presence of two witnesses.

WILLIAM ROWLAND EDWARDS.
